UNITED STATES PATENT OFFICE

ADOLPH STOELTING, OF KIEL, WISCONSIN, ASSIGNOR TO STOELTING BROTHERS CO.,
OF KIEL, WISCONSIN

VAT

Application filed April 30, 1928. Serial No. 274,112.

This invention relates to vats and is particularly directed to the lower jacket for a vat.

Objects of this invention are to provide a novel form of container or lower jacket for a vat which is so constructed that it is extremely strong and braced against breaking either due to separation or due to sagging.

Further objects are to provide a construction for vat jackets, which is easy to produce by ordinary shop methods, which is relatively cheap to make, and which is so made that it is held against warping when the wooden portions thereof become moistened, and which will withstand a considerable weight without any danger of breaking.

An embodiment of the invention is shown in the accompanying drawings in which:

- Figure 1 is a plan view;
- 20 Figure 2 is a longitudinal sectional view;
- Figure 3 is a sectional view on the line 3—3 of Figure 1.

Referring to the drawings, it will be seen that the container or lower jacket for the vat consists of side members 1, end members 2, and a bottom 3 which slants downwardly towards its center. The vat is provided at regular intervals with bottom metal straps 4 which extend completely across from one

30 side to the other.

Further, at spaced points along the side

members 1, inset metal strap members 5 are provided and are positioned adjacent the bottom strap members 4, as is clearly shown

35 in Figure 3.

L-shaped brace members are secured to the vertical strap members 5 or reenforcing members. These L-shaped members consist of a vertical wedge-shaped portion 6 and an inwardly directed arm 7. The arm 7 or leg of the L-shaped member is provided with side flanges 8 to secure the maximum stiffness and strength with the minimum weight. Further, the inwardly extending leg of the 40 L-shaped member is provided with an end flange 9 which is apertured to receive the tie bolt 10. The L-shaped members have the legs 7 bolted to the bottom strap members 4 and the legs 6 bolted or otherwise secured to the 45 strap members 5, preferably screws being

used in the latter case and tapped into the thickened leg members 6, so as to avoid projecting nut heads which might injure the removable vat 11.

The vat is carried by a plurality of stools 55 or supports which consists of the vertical legs 12 provided with the connecting web 13 and the supporting beam 14. These legs are removably secured to the bottom of the vat at regular intervals by means of the lag 60 screws 15.

The heating of the vat may be secured in any suitable manner, as by means of the centrally arranged steam pipe 15' which is positioned in the lowest portion of the vat casing 65 or jacket, and which is provided with outlet portions, as shown in Figure 1.

It is to be noted particularly that an extremely strong and serviceable and easily produced construction has been provided by 70 this invention and that the L-shaped bracing members are tied to the outer vertical strap members so that the vat is held against spreading and also against sagging. The tightening of the tie bolts 10 which pass 75 through apertures in the end flange 9 of opposed L-shaped members, urges these members towards each other and thus provides a vertical component of the force exerted by the tie bolts, which prevent sagging of the 80 bottom of the vat jacket. In addition to this, the L-shaped members are drawn inwardly and consequently prevent spreading of the sides of the vat jacket.

Although the invention has been described 85 in considerable detail, such description is intended as illustrative rather than limiting as the invention may be variously embodied and as the scope of such invention is to be determined as claimed.

I claim:

1. In a vat construction, the combination of a container having side, end, and bottom walls, a plurality of L-shaped members positioned within the vat and having bottom 95 members and vertical members forming the legs of the L-shaped member secured to the bottom and side walls of the container respectively, reenforcing straps mounted on the outer side of the bottom and side walls and 100

secured to the legs of the L-shaped members, and tie bolts extending between the L-shaped members and connected to the L-shaped members adjacent their innermost ends.

- 5 2. In a vat construction, the combination of a container having side, end, and bottom walls, a plurality of L-shaped members positioned within the vat and having bottom members and vertical members forming the legs of the L-shaped member secured to the bottom and side walls of the container respectively, reinforcing straps mounted on the outer side of the bottom and side walls and secured to the legs of the L-shaped members, and tie bolts extending between the L-shaped members and connected to the L-shaped members adjacent their innermost ends, said L-shaped members having channel-shaped bottom portions.
- 10 3. A jacket for a vat comprising a bottom downwardly slanting towards its center, a pair of vertical side walls, a pair of end walls, strap members positioned beneath the bottom, strap members extending vertically on the outer sides of the side walls, a plurality of L-shaped members having vertical arms bolted to the vertical strap members and having lower arms conforming to the sloping bottom and bolted to the bottom strap members, said L-shaped members being arranged in pairs and having opposed upstanding flanges, tie bolts extending between the L-shaped members and passing through such upstanding flanges.
- 15 4. In testimony that I claim the foregoing I have hereunto set my hand at Kiel, in the county of Manitowoc and State of Wisconsin.

ADOLPH STOELTING.
